SHEET DELIVERY APPARATUS.

No. 324,245.

Patented Aug. 11, 1885.

UNITED STATES PATENT OFFICE.

GEORGE P. FENNER, OF NEW LONDON, CONNECTICUT.

SHEET-DELIVERY APPARATUS.

SPECIFICATION forming part of Letters Patent No. 324,245, dated August 11, 1885.

Application filed December 18, 1884. (No model.)

To all whom it may concern:

Be it known that I, GEORGE P. FENNER, a citizen of the United States, residing at New London, in the county of New London and State of Connecticut, have invented new and useful Improvements in Sheet-Delivery Apparatus, of which the following is a specification.

The object of my invention is to produce a sheet-delivery apparatus for printing-presses, and especially cylinder-presses, whereby the sheet may be delivered with its freshly-printed side upward and without being touched on such side by any part of the apparatus. This object I have accomplished, as hereinafter described and illustrated in the accompanying drawings, in which—

Figure 1 is a side elevation of my apparatus, showing it applied to a printing-press. Fig. 2 is a plan or top view thereof. Figs. 3 and 4 are details, and will be referred to as this description progresses.

Similar letters indicate corresponding parts.

The letter A designates the press-frame, constructed to support the revolving impression-cylinder B and the type-bed C in proper relation to each other. D indicates a spur-wheel arranged on a shaft, D', Fig. 1, to engage a horizontal row or series of studs, C', on a pendent portion of the bed, alternately above and below the plane of the studs, for imparting the proper motion to the bed, and B', Fig. 2, denotes a cog-wheel arranged on the shaft of the cylinder to gear with the driving-shaft for imparting the proper motion to the cylinder.

In a suitable cavity of the cylinder B are arranged the usual grippers, B³, for holding the sheet to be printed on the cylinder, those grippers being opened and closed by trip-pins B⁴, acting on cam B⁵, Fig. 2, of the gripper-shaft B⁶. The cylinder B makes two revolutions during a complete traverse of the bed in both directions, and to adapt the gripper B³ to such motion of the cylinder the trip-pins B⁴ are alternately thrown out of action by means of a cam and cam-levers, the whole constituting a press of well-known construction.

To one of the longitudinal edges of the bed C is secured a rack, F, which meshes into a gear, G, mounted on a stud, a, projecting from

the frame A. This gear G, to which reverse motions are imparted by the rack F, as the same receives a reciprocating motion by the type-bed, carries a chain-wheel, b, over which a chain, b', passes for transmitting the reverse motions of gear G to the shaft h. This shaft turns in bearings in the frame A, and on it are mounted chain-wheels c c, over which chains d d pass to pulleys e e. These chains d d serve to impart a reciprocating motion to a sliding carriage, I, which is secured to them at f f. In this carriage I are bearings for the shafts g g', which respectively carry tape-rolls H H', the relative distance between which remains unchanged as the carriage is carried back and forth on the guide-rods J J by the chains d d. These guide-rods are rigidly secured to the frame A of the press, and on them are fixed brackets K K, the upper ends of which serve as bearings for the shaft i, carrying the chain-pulleys e e, while the lower serve as bearings for the shaft j, carrying the fixed tape-roll L. In the frame near the inner ends of the guide-rods J J are formed bearings for a shaft, k, on which are mounted the tape-roll M and the pulley N. To this shaft a continuous motion in the direction of arrow 1, Figs. 1 and 3, is transmitted by means of a belt, l, which passes over pulley N, Fig. 2, and the cylinder B. The tapes m, for carrying the printed sheet from the cylinder, as they pass over the various tape-rolls H, H', L, and M, (see Figs. 1 and 3,) have a continuous motion in the direction of arrow 2, Figs. 1, 2, and 3, independent of any motion of carriage I. Adjustable sheet-guides O are placed between the tape-roll M and the cylinder B in such a manner that when the sheet leaves the cylinder the front edge is supported and guided onto the tapes m.

To raise the edge of the sheet from the cylinder after it has been printed and while the grippers B³ are open a series of sheet-lifters, n, are mounted on a shaft, o, which has its bearings in the cylinder B, and one end of which is provided with a lever, p. This lever carries at one end a link, q, provided with a friction-roll, r, which bears on a cam, s, mounted on the gripper-shaft B⁶. (See Fig. 4.)

While the grippers are closed, as in Fig. 1, the sheet-lifters n lie below the surface of the cylinder, but as the grippers are turned open and the cam s revolves the lever p is raised

against the action of the spring *t*, Fig. 1, thereby turning the shaft *o* and raising the sheet-lifters *n* to the position shown in Fig. 3, and in dotted lines in Fig. 4, thereby raising 5 the edge of the sheet from the cylinder and onto the sheet-guides *O*, thus insuring a positive delivery from the impression-cylinder onto the tapes *m*.

The operation of my apparatus is as follows: The sheet as it is fed from the table 10 is grasped by the grippers *B*³ in the cylinder *B* and is carried over the type-bed *C*, where it is printed, and as the cylinder begins to make its second revolution the grippers are opened, thereby bringing the sheet-lifting device above described into play, 15 and the sheet is carried over the sheet-guides *O* onto the moving tapes *m*, the position of which at this stage of the operation is shown in Fig. 3. As the revolution of the cylinder continues and the type-bed carrying the rack *F* begins its reverse motion the chains move in 20 the direction of the arrows in Fig. 3, causing the carriage *I* to move in the direction of the arrow 3 until the type-bed has reached the 25 position shown in Fig. 1, where the carriage *I* will be in the position shown in said figure. The cylinder is then in position to take a new sheet, and as the type-bed passes under 30 the cylinder the rack secured to it will turn the gear *G* and chains *b'* and *d d*, as indicated by arrows *Z*, in Fig. 1, thereby moving the carriage *I* away from under the sheet, while the continuous forward motion of the tapes *m* 35 causes it to run off the carriage and against stops *Q* and drop onto the table *P*, thereby completing the operation and delivering the sheet without having touched its printed face.

What I claim as new, and desire to secure 40 by Letters Patent, is—

1. The combination, substantially as hereinbefore described, with the impression-cylinder and the type-bed, of the tape-roll *M*, means, substantially such as described, for imparting 45 to this tape-roll a continuous revolving motion

in one and the same direction, the tape-carriage *I* carried by guides, and mechanism, substantially such as described, for imparting to this tape-carriage a reciprocating motion in the line of travel of the tapes. 50

2. The combination, substantially as hereinbefore described, with the impression-cylinder and the type-bed, of the sheet-delivery tapes *m*, passing over the rolls *M L*, which revolve in fixed bearings, and over the rolls *H H'*, which have their bearings in the tape-carriage *I*, the belt *l* for imparting to the tape-roll *M* a continuous revolving motion in the same direction, and mechanism, substantially such as described, for imparting to the tape-carriage a 60 reciprocating motion. 55

3. The combination, substantially as hereinbefore described, with the impression-cylinder and the type-bed, of the sheet-delivery tapes *m*, passing over the rolls *M L*, which revolve in fixed bearings, and over the rolls *H H'*, which have their bearings in the tape-carriage *I*, means, substantially such as described, for imparting to tape-roll *M* a continuous revolving motion, mechanism, substantially such as described, for imparting to the tape-carriage a reciprocating motion, the sheet-guides *O*, and the sheet-lifters *n*. 70

4. The combination, substantially as hereinbefore described, with the impression-cylinder and the type-bed, of the tape-carriage *I*, the endless chains *d*, to which the tape-carriage is attached, the endless chain *b'*, for imparting to chains *d* a reverse motion, the tape-rolls *M* and *L*, mounted in fixed bearings, and the belt *l* for imparting a continuous revolving motion to the roll *M*. 75

In testimony whereof I have hereunto set my hand and seal in the presence of two subscribing witnesses.

GEORGE P. FENNER. [L.S.]
